UNITED STATES PATENT OFFICE

92,158

DESIGN FOR A BASE UNIT FOR A CABINET OR SIMILAR ARTICLE

Howard E. Blood, Detroit, Mich., assignor to
Norge Corporation, a corporation of Michigan

Application August 19, 1933, Serial No. 49,069

Term of patent 14 years

To all whom it may concern

Be it known that I, HOWARD E. BLOOD, a citizen of the United States and a resident of Detroit, in the county of Wayne and State of Michigan, have invented a new, original, and ornamental Design for a Base Unit for a Cabinet or Similar Article, of which the following is a specification, reference being had to the accompanying drawing, constituting a part hereof:

The figure is a perspective view of my design for a base unit or similar article and shown as supporting a cabinet the lower portion of which is shown together with the rear supports in dotted lines. The dotted line disclosure is not claimed.

My design for a base unit or similar article which is adapted to provide a support for a cabinet or the like is characterized by the massive appearance of the relatively short supporting legs and the relatively broad low arch formed between such legs.

I claim:

The ornamental design for a base unit for a cabinet or similar article substantially as shown and described.

In testimony whereof, I have hereunto subscribed my name this 15th day of August, 1933.

HOWARD E. BLOOD.
